UNITED STATES PATENT OFFICE.

PHILIP B. PARK, OF ALEXANDRIA, VIRGINIA.

GANG-PLANK.

1,151,816.

Specification of Letters Patent. Patented Aug. 31, 1915.

Application filed July 9, 1914. Serial No. 849,963.

To all whom it may concern:

Be it known that I, PHILIP B. PARK, a citizen of the United States, residing at Alexandria, in the county of Alexandria 5 and State of Virginia, have invented certain new and useful Improvements in Gang-Planks, of which the following is a specification.

My invention relates to new and useful 10 improvements in gang-planks.

The object of my invention is to provide a gang-plank for bridging over the space between a car and a stationary platform or between cars placed side by side for the purpose of transferring the freight from one car to another, standing on parallel tracks in the freight transfer yards of railroads.

Another object of my invention is to provide a gang-plank having adjustable locking means whereby the gang-plank may be locked and rigidly held between cars or a car and platform, thereby avoiding accidents which result from the plank being accidentally moved under the weight of the 25 article being transferred from one car to another and falling to the ground.

A further object of my invention is to provide a gang-plank having interlocking arms pivotally secured to a disk journaled 30 on the under surface of the plank; said disk having secured thereon a ratchet-wheel, engaging a ratchet for locking the arms in the position desired.

A still further object of my invention is 35 to provide a gang-plank having locking means which may be adjusted to the varying lengths and heights of the platforms or cars to be bridged, and which may be constructed of steel, wood or other material, 40 and provided with a plurality of strengthening ribs, extending longitudinally the plank and secured upon the under surface thereof.

With the above and other objects in view, my invention consists in the details of construction and in the combination and arrangements of the several parts as illustrated in the accompanying drawing, forming a part of this specification, and in which;

Figure 1 is a sectional view, showing my 50 improved gang-plank as used to bridge between two cars and also between a car and platform. Fig. 2 is a top plan view. Fig. 3 is a bottom plan view. Fig. 4 is a sectional view on the line X—X of Fig. 3.

55 In the drawing like letters and reference

characters denote corresponding parts in the several views, and in which—

1 indicates the main bridge portion of my improved gang-plank, which may be constructed of iron, wood, or cement but preferably of steel, and is provided with a plurality of longitudinal strengthening ribs, 2—2. The ribs may be of different widths and where the bridge portion of the plank is of comparatively narrow width a single 65 strengthening rib attached to each side will be sufficient to strengthen the main body portion of the plank, but in a gang-plank having considerable width, and used to transfer heavy articles, it is preferable to 70 provide additional strengthening ribs. The ends of the plank may be made round or sloped, so that the wheels of a truck may pass over the edge of the plank without any great resistance.

75 The locking means I secure upon the under surface of the gang-plank and which comprises a disk, 3, having a shaft, 4, provided with square ends adapted to be operated by means of a wrench, or, if preferable, a crank handle having a socket adapted to fit over the square ends. I also provide an aperture (as shown in Fig. 2) in the central part of the platform through which the end of shaft 4 projects and which permits the disk to be rotated from the top surface of the plank. I pivotally attach to the disk arms 5—5 having rigidly connected intermediate their length arms 6—6; said arms being approximately right angle 85 in shape. Secured to the gang-plank are clips 6^a 6^a, 6^b 6^b, beneath which the arms may be reciprocated when the disk is rotated. The ends of the arms, 5—5 and 6—6, are bent at right angles to the main portion 95 of the arms, as shown at 7—7, Fig. 4. I also provide sharpened points on the extension 7—7, whereby the end of the arm may easily penetrate the frame work of a car or platform. In a steel car, or where the main 100 beam of the car is made of metal, the end portion, 7, is adapted to be inserted under the beam, thus preventing the plank from being accidentally moved. The disk I also provide with a ratchet-wheel, 8, which may be formed integrally with the disk or connected thereto by any suitable means. A V-shaped brace, 9, having its ends secured to one of the strengthening ribs, projects over the disk and forms a bearing for the shaft 4.

105 110

Upon one arm of the brace a ratchet, 10, having spring, 11, for holding the ratchet in contact with the teeth of the ratchet wheel.

The operation of my device is as follows:

- 5 One end of the plank rests upon the platform, or in a case where it is used between cars, upon the floor of a car, and the other end extends to the car or platform to which the freight is to be transferred, after which
- 10 a wrench or crank handle may be attached upon either end of the shaft and the disk rotated. The portion of the disk, as will be plainly seen by an examination of Fig. 3, moves the ends of the arms, 5—5 and 6—6,
- 15 toward each end of the gang-plank respectively, and such a movement brings the ends of the arms in contact with the frame of the car or platform, or, as stated, where the platform or car may be constructed of
- 20 metal, the arms may slide over the under surface of the car sill, or should it happen that the car sill is of greater width than the bent end portions of the arms, the points may be forced against the outer surface and
- 25 held rigidly in such position by means of the ratchet engaging the teeth of the ratchet wheel on the operating disk.

It is believed from the foregoing description of the construction and operation that my invention may be easily and readily understood, it being noted that changes may be made in the details of construction and in the size of the same without departing from the scope of my invention.

Having fully described my invention, what I claim as new and desire to secure by Letters Patent is:—

1. In a gang-plank, a platform provided with rounded ends and having a plurality of strengthening ribs secured to the under surface thereof, arms reciprocally mounted on the under surface, a rotating disk for imparting movement to said arms, a ratchet wheel secured upon said disk, and means for

holding said ratchet wheel in a locked position, substantially as described.

2. In a gang-plank, a platform having rounded ends and provided with a plurality of strengthening ribs secured to the under surface thereof, a disk suitably mounted on said platform and having horizontally extending arms pivotally secured thereto, said horizontally extending arms having arms approximately right angle in shape secured thereon, means for permitting a reciprocatory movement of the arms, means for operating the disk from either side of the gang-plank, and means for holding said disk in a locked position, substantially as described.

3. In a gang-plank, having a platform with rounded ends, a plurality of strengthening ribs longitudinally secured on the under surface thereof, clips secured to said platform, a disk suitably mounted on the under surface of the platform, a brace having its ends secured to one of said strengthening ribs, forming a bearing for the disk shaft, a ratchet-wheel carried by said disk, arms pivotally secured upon opposite sides of said disk adapted to reciprocate through said clips, as and for the purpose set forth.

4. In a gang-plank, a platform having a plurality of strengthening ribs, clips secured upon the under surface of said platform, a disk having a ratchet-wheel secured thereon, arms pivotally secured to said disk and extending toward each end of said plank, and means including said ratchet-wheel for holding said arms and disk in a locked position, as and for the purpose described.

In testimony whereof I affix my signature in presence of two witnesses.

PHILIP B. PARK.
